United States Patent Office

Des. 194,525
Patented Feb. 5, 1963

194,525

BOOKKEEPING FILE

Thomas E. D'Arcy, 2619 S. Lincoln, Denver, Colo.

Filed July 13, 1961, Ser. No. 65,907

Term of patent 14 years

(Cl. D87—5)

FIG. 1.

FIG. 5.

FIG. 2.

FIG. 3.

FIG. 4.

FIGURE 1 is a top plan view of a bookkeeping file showing my new design;

FIGURE 2 is a front elevational view;

FIGURE 3 is a view of one end thereof with the other end being similar;

FIGURE 4 is a view in perspective with the hinged lid being shown in the open position; and,

FIGURE 5 is a view in perspective with the hinged lid being shown in the open position; and,

I claim:

The ornamental design for a bookkeeping file, as shown.
